Joseph Melville, Long Beach, N. Y.

Application April 4, 1951, Serial No. 14,708

Term of patent 3½ years

(Cl. D3—25)

To all whom it may concern:

Be it known that I, Joseph Melville, a citizen of the United States of America, residing in Long Beach, county of Nassau, and State of New York have invented a new, original, and ornamental Design for a Man's Shirt or Similar Article, of which the following is a specification, reference being had to the accompanying drawing, forming part thereof, wherein,

I claim:

The ornamental design for a man's shirt or similar article, substantially as shown.

JOSEPH MELVILLE.
